UNITED STATES PATENT OFFICE

167,697

BICYCLE TRAINER

Moe Kosack, Brooklyn, N. Y.

Application September 10, 1951, Serial No. 16,594

Term of patent 7 years

(Cl. D90—8)

To all whom it may concern:

Be it known that I, Moe Kosack, a citizen of the United States of America, residing at Brooklyn, in the county of Kings and State of New York, have invented a new, original, and ornamental Design for a Bicycle Trainer, of which the following is a specification, reference being had to the accompanying drawing, forming a part thereof.

Fig. 1 is a front elevational view of a bicycle trainer, showing my new design.

Fig. 2 is a top plan view thereof.

Fig. 3 is a side elevational view thereof.

Fig. 4 is a rear elevational view thereof.

I claim:

The ornamental design for a bicycle trainer, substantially as shown.

MOE KOSACK.
